(57) CLAIM

The ornamental design for a blue ring for a wall faucet, as shown and described.

DESCRIPTION

The file of this patent contains at least one drawing executed in color. Copies of this patent with color drawings will be provided by the Office upon request and payment of the necessary fee.

FIG. 1 is a perspective view of a blue ring for a wall faucet. FIG. 2 is a top perspective view of the blue ring for a wall faucet of FIG. 1.

FIG. 3 is a bottom perspective view of the blue ring for a wall faucet of FIG. 1.

FIG. 4 is a top view of the blue ring for a wall faucet of FIG. 1.

FIG. 5 is a bottom view of the blue ring for a wall faucet of FIG. 1.

FIG. 6 is a front view of the blue ring for a wall faucet of FIG. 1.

FIG. 7 is a back view of the blue ring for a wall faucet of FIG. 1.

FIG. 8 is a right side view of the blue ring for a wall faucet of FIG. 1; and,

FIG. 9 is a left side view of the blue ring for a wall faucet of FIG. 1.

The broken lines depict portions of the blue ring for a wall faucet that form no part of the claimed design and the dash-dot lines define the boundaries of the blue ring for a wall faucet that form no part of the claimed design.
